AIR OR GAS LIFT PUMP

George K. Taggart, Fort Worth, Tex.

Application May 10, 1933, Serial No. 670,288

3 Claims. (Cl. 103—232)

This invention relates to oil or water well equipment and it has particular reference to pumping facilities for producing oil or extracting water from subterranean areas by air or gas pressure and its principal object resides in the provision of apparatus capable of attachment within a conventional oil or water well and calculated to receive sufficient fluid pressure to force a maximum amount of liquid to the earth's surface at a minimum cost.

Another object of the invention resides in the provision of such a device as will greatly reduce the usual attendant production cost of oil wells, and the like, and afford a means whereby maximum results can be realized. A particularly desirable feature of the invention is manifest in the simplicity of construction and dependability of its operation, lifting a large column of fluid, by introduction of air or gas from the earth's surface at a point adjacent to or remote from the mouth of the well. The natural gas pressure in the well can also be augmented by the introduction of air or gas pressure from the earth's surface to assist in lifting the column of liquid.

Still another object of the invention is manifest in the provision of a means whereby the lifting force can be completely and easily controlled at the earth's surface thereby enabling the production operation to be conducted at will, that is to say, affording a means whereby production can be started or stopped as desired.

A still further object of the invention resides in the provision of a device which is particularly advantageous in the oil fields where production has been materially curtailed and where only a given amount of oil is allowed to be produced in a given period of time and where pumping is periodical rather than continuous. The invention, as outlined in the foregoing paragraphs, is capable of operation at will and enables the producer to reduce his production expense yet without sacrificing efficiency in such production.

While the foregoing objects are paramount, other and lesser objects will become manifest as the description proceeds taken in connection with the appended drawings wherein:

Figure 1 is a vertical cross-sectional elevational view of the uppermost portion of the invention projecting above the derrick floor.

Figure 2 is a vertical cross-sectional view of the invention illustrating the valve arrangement in the lowermost portion thereof and which projects into the well.

Figure 3 is a lateral cross-sectional view taken on lines 3—3 of Figure 3.

Figure 4 is a lateral cross-sectional view taken on lines 4—4 of Figure 2, and

Figure 5 is a complete layout of the invention.

It will accordingly be presently shown that a means of positive control from a point outside of the well is afforded by which the fluid discharge annular eductor 26 and the air line 25 can be left free of fluid when the pumping period is completed, and whereby the said annular eductor 26 and the air line 25 can be kept in that condition until the fluid valve 34 in the foot piece is manually opened, irrespective of whether compressed air or gas is introduced into the pump or not. The fluid discharge annular eductor being empty at the beginning of the pumping period, thereby allowing compressed air or gas to pass freely down through the air line 25 and thence upward through the annular eductor 26 before the fluid valve is opened, obviates the necessity of excessive pressures in "kicking off" or starting the well to flowing, as is usual in air lift pumps.

One form of this invention is illustrated in the accompanying drawings. The collar 24 is the

top collar of the outside casing 28 of a well. A fluid annular eductor 26 contains a compressed air tubing 30.

A string of tubing 29 is hung from a special collar 19, which is fluid and gas tight,

with respect to a cross 18, due to its having a ground joint seat in the cross 18. The cross 18 is threaded into the collar 24. Two openings 22

and 23, one of which may be plugged, as for instance by a bull plug 20, and the other carrying a vent line 21, provides means of discharge (when used in an oil well) should the well flow through the casing 28. Another cross 13 is threaded into the cross 18, and is provided with two outlets 16

and 17, one or both of which can be used for discharge of the fluid and air and/or gas, that vents through the annular eductor 26.

A device is illustrated in Figure 1 that will positively and efficiently raise or lower the air tubing 30 in the well. The tubing 30 acts as a stem for the fluid valve 34 in the lowermost end of the assembly as illustrated in Figure 2. The air tubing 30 is supported by a collar 2 on the plate 3

which in turn is supported by a screw jack 7, which slips loosely around the tubing 30.

A nut 4 which is provided with square female threads mesh with the male threads on the screw jack 7. The nut 4 rests on a ball bearing race 5,

which in turn sets in a recess on top of the support 6. The nut 4 is capstan headed having

drilled holes into which a lever handle 9 can be inserted to rotate the nut 4, which raises or lowers the screw jack 7 and consequently raises or lowers the tubing 30 and the valve 34 in the same manner, since the tubing 30 is suspended from a collar on the screw jack 7. A guide 10 is keyed rigidly to the lower end of the screw jack 7. The outer extremities of the guide 10 have recesses which engage the splines 8, and which cause the screw jack 7 and the tubing 30 to move upwardly and downwardly without turning or twisting as the nut 4 is rotated. A stuffing box 11 prevents leakage of air or fluid around the tubing 30 when the same is raised or lowered. The foot piece is threaded onto the tubing 29. A valve seat 35 is turned in the foot piece and is closed or opened by lowering or raising the valve 34, which latter is blind and is threaded onto the bottom of the air tubing 30. The lower part of the tubing 30 is provided with perforations which are sufficient in area to allow the escape of compressed air or gas into the annular eductor 26 and still maintain the proper back pressure within the tubing 30. The vertical guides 33 keep the valve 34 centered in the tubing 30 and prevents chattering when the valve 34 is raised to allow the entrance of fluid into the annular eductor 26. A check or standing valve 39 may be threaded into the collar 38 an arbitrary distance below the foot piece. A standing valve 39 may be used to prevent any possibility of compressed air or gas exerting any back pressure on the producing sands. Perforations 41 are placed in the tubing anchor 40 below the standing valve 39.

When it is desired to start the well pumping, compressed air or gas is forced downwardly through the tubing 30, which latter is practically empty of oil or water, as is also the annular eductor 26, due to the valve 34 being situated in its seat 35. Should a small amount of oil or/and water have leaked into the eductor 26 and/or tubing 30 during the shut down period, it would be easily blown out when air is first admitted without excessive air or gas pressure being required. The air valve 4 is then adjusted to allow a proper amount of air to pass into the tubing 30 and circulate freely downwardly to the foot piece and then upwardly through the annular eductor 26. The valve 34 is then gradually opened by revolving the nut 4 on the screw jack 5 until a maximum amount of oil and/or water is passing upwardly through the tubing 40, the standing valve 39 and into the annular eductor 26, for the particular amount of air or gas being used at that time, and is aerated or lightened by its comingling with the compressed air or gas and so passes up through the annular eductor 26 and is discharged from the well through one of two openings, 14 or 15, in the cross 13 to a container such as a tank or the like not shown. The amount of air entering and the amount of liquid being discharged can thus be regulated from points outside of the well to obtain maximum efficiency.

To cease the pumping operation, the valve 34 is lowered into its seat 35 by revolving the nut 4 on the screw jack 5, at the top of the well, while

the compressed air or gas is still circulating upwardly through the annular eductor 26, thereby cleaning the annular eductor 26 of oil and/or water.

Manifestly, the construction shown and herein described is capable of considerable modification by those skilled in the art, such modification, however, as is considered within the spirit and intent of the invention is also considered within the scope of the appended claims.

What is claimed is:

1. In combination with a bored well casing and a string of tubing, an air tube, concentrically arranged within the said tubing, a valve seat air disposed within the said tube, a valve closure fixed upon the lowermost end of the said air tube and capable of engaging the said valve seat, air outlets for the said air tube, an exteriorly threaded sleeve member surrounding the upper end of the said air tube having a capstan threaded thereupon, guide means secured to the lowermost end of the said threaded sleeve member to prevent the rotation of the latter when the said capstan is rotated thereon to move the said air tube vertically to actuate the said valve.

2. A gas or air lift pump capable of operation in combination with an oil well casing and string of tubing, an air tube concentrically arranged within the said tubing and capable of vertical movement therein, a valve seat positioned within the said string of tubing and a valve closure fixed upon the lowermost end of the said air tube, air outlets for said air tubing, a cylindrical housing arranged upon the uppermost end of the said casing, an exteriorly threaded tubular member concentrically arranged within the said housing and surrounding the uppermost end of the said air tube, a capstan threaded upon the said tubular member, a bearing race seated upon the uppermost end of the said cylinder capable of supporting the said capstan, guide means restraining the said threaded sleeve member against rotation when the said capstan is rotated thereon to vertically move the said air tube to actuate the said valve.

3. In combination with a bored well casing, and string of tubing, cross-heads arranged in superimposed relationship in the head of the said casing, a cylindrical housing vertically arranged upon the said cross-heads, an air tube concentrically arranged within the said cylindrical housing and extending downwardly through the said tubing capable of vertical adjustment therein, a valve seat positioned in the said tubing, a valve closure fixed at the lowermost end of the said air tube capable of engaging the said valve seat, air outlets arranged in the said air tube, an exteriorly threaded sleeve surrounding the said air tube within the said cylindrical housing freely engaging the outer walls of the said air tube, an interiorly threaded capstan positioned upon the said sleeve and capable of vertically moving the same, guide means secured to the said sleeve capable of restraining the latter against rotation when the said capstan is threaded thereupon to move the said air tube upwardly or downwardly within the said string of tubing to actuate the said valve.
